Albert Peacock

UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

TABULAR BAR AND STOP.

1,247,401.

Specification of Letters Patent. Patented Nov. 20, 1917.

Application filed April 25, 1917. Serial No. 164,370.

To all whom it may concern:

Be it known that I, EDWARD B. HESS, a citizen of the United States, and a resident of the borough of Brooklyn, in the city of New York, county of Kings, and State of New York, have invented certain new and useful Improvements in Tabular Bars and Stops, of which the following is a specification.

10 The present invention relates generally to typewriting or like machines, and has more particularly reference to what is generally known as tabular bars and stops by means of which, when the carriage is released in a well-known manner, the carriage may move transversely to a greater extent than a single letter-space distance.

20 A typical construction of bar and stop, as the art is at present constituted, consists in a tabular bar having vertical slots in its side face, said bar extending transversely of the machine; together with stops that are removably seated on the bar. In the particular form, under consideration, the vertical 25 slots are spaced letter-space distances apart, and the stops are of sheet material and provided with a lower bifurcated end, the legs of which straddle the bar and slide in the vertical slots of the bar. The walls of the slot, in addition to acting as a positioning 30 means determining the correct position of the stops in respect to a scale usually carried by the bar, also act to prevent lateral displacement of the stops. In practice it has, 35 however, been found that upward displacement out of the slots is liable to take place, especially after the stops have been in use for some time and after they have become worn due to their repeated insertion and 40 withdrawal from the tabular bar.

The main object of the invention is to prevent accidental upward displacement of the tabular stop with respect to the bar and to provide simple and effective means for accomplishing this purpose.

One feature of the invention resides in providing means to prevent accidental upward displacement of the stops out of the slots.

50 Still another feature of the invention resides in a tabular bar having a longitudinal channel, together with a tabular stop having means extending into the channel for preventing displacement of the stop.

Another feature of the invention resides in providing spring means for yieldingly holding the stop in position to prevent its displacement. In a preferred form of the invention herein disclosed, said spring means are carried by each individual stop so that the stops are held in individual spring-pressed relation on the bar. In the particular embodiment, here chosen for illustration, the tabular bar is provided with a longitudinal channel preferably arranged in the upper face of the bar, and the spring means are, in the particular form here described, located between the legs of the lower bifurcated end of the stop and project into the channel and engage with the wall or walls thereof.

In the accompanying drawings: Figure 1 is a top plan view of a tabular bar, embodying a preferred form of the invention, shown mounted in the end frames of the carriage and showing also the relation of the paper table brackets to the parts, and further illustrating several stops in position, one of said stops being in section.

Fig. 2 is a side elevation of one end of the bar with stops in position, part of the bar being broken away to show the channel, and one of the stops being in section.

Fig. 3 is an end view of the tabular bar.

Fig. 4 is a transverse vertical sectional view through the bar taken on the line 4-4 of Fig. 1 showing a preferred form of stop in position.

Fig. 5 is a view similar to Fig. 4 showing a modified construction of stop, and

Fig. 6 is also a view similar to Fig. 4 showing another modified construction of stop.

The tabular bar 7 is generally square in cross section as shown and is reduced at its ends 8 to provide threaded stems flattened on the top. A convenient method of adjustably mounting said bar in the laterally moving carriage consists in passing the reduced portions 8 through the end frames 9 of the carriage and through the paper table brackets 10. Said end frames and brackets are provided with openings 11 of slightly larger diameter than the reduced end portions 8, and two lock nuts 12, at each end, are provided for locking the bar 7 in its adjusted position with respect to the end frames 9 and paper-table brackets 10.

The main body of the tabular bar 7 is

provided with vertical slots 13 in its side faces, which slots are spaced letter distances apart and are properly related to a scale indicated on the upper face of the bar 7 as shown in Fig. 1. Extending longitudinally of the bar is a channel 14 opening into the upper face of the bar.

- 15 indicates a stop, shown here as being made from sheet metal, whose lower end is bifurcated to provide legs 16 which straddle the bar, and which are spaced apart to permit said legs to slidably enter the vertical slots 13 when straddling the bar. The upper portion of the stop is preferably shaped to 15 form a handle or grasping portion here shown as a ring 17. Intermediate the legs 16 of the stop suitable means are provided for engaging the channel of the bar to prevent upward displacement of the stop out 20 of the vertical slots. In the form shown in Figs. 1 and 4, a spring tongue 18 is formed integral with the blank constituting the stop, said spring tongue or projection depending between the legs 16 of the stop, and being 25 provided with an enlargement 19 to engage one of the side walls of the channel. It will be understood that when the stop straddles the bar, the projection 18 extends into the channel and by its frictional engagement 30 with the wall of the same tends to prevent upward accidental displacement of the stop. At the same time, when a sufficient upward intentional pull is exerted on the stop, said stop will readily be withdrawn from the bar. 35 In Fig. 5 the stop 15 is provided with a separate spring member 20 suitably secured between the legs 16 and terminating at its lower end in a rounded head 21 engaging both side walls of the channel 14.
- 40 In Fig. 6 the spring means of the stop 15 take the form of two depending springs 22 suitably secured between the legs 16 of the said stop. Each spring 22 is provided with a small curl or head 23 at its lower end and

each head 23 is adapted to engage with one side wall of the channel 14.

From the foregoing it follows that the tabular bar 7 is adapted to receive a stop 15 in any letter-space position by reason of the vertical slots 13 of the bar and coöperating 50 legs 16 of the stop, and that this stop is readily removable from its position on the bar, but that, nevertheless, the spring means and channel afford sufficient frictional tension to prevent an accidental upward displacement of the stop. It will also be noted that, in the form herein disclosed each stop is individually spring pressed which tends to insure the proper amount of tension on each stop, and permits any stop to be removed from the bar without disturbing the remainder.

I claim:

1. A tabular bar having vertical slots in its side faces spaced letter-distance apart to receive a tabular stop, an open longitudinal channel in the top face of the bar, a tabular stop having a bifurcated lower end which straddles the bar and the legs of which engage in the vertical slots, and means carried 65 by the stop intermediate its legs and projecting into the channel for holding the stop against displacement.

2. A tabular bar having vertical slots in its side faces spaced letter-distance apart to receive a tabular stop, an open longitudinal channel in the top face of the bar, a tabular stop having a bifurcated lower end which straddles the bar and the legs of which engage in the vertical slots, and spring means 70 carried by the stop intermediate its legs and projecting into the channel for holding the stop against displacement.

Signed at New York city, in the county of New York and State of New York, this 23 80 day of April, 1917.

EDWARD B. HESS.
